[57] CLAIM

The ornamental design for a telephone apparatus, as shown.

DESCRIPTION

FIG. 1 is a top perspective view of a telephone apparatus showing my new design;

FIG. 2 is a top perspective view as seen from the opposite side of FIG. 1;

FIG. 3 is a front elevation thereof;

FIG. 4 is a top plan view thereof;

FIG. 5 is a side elevation thereof;

FIG. 6 is a bottom plan view thereof;

FIG. 7 is a rear elevation thereof; and

FIG. 8 is an elevation as seen from the opposite side of

FIG. 5.

The bottom is planar and non-ornamental.

*Fig.1.**Fig.2.**Fig. 3.**Fig. 4.**Fig. 5.**Fig.6.**Fig.7.**Fig.8.*
